UNITED STATES PATENT OFFICE.

CORNELIUS B. CORCORAN, OF NEW YORK, N. Y., ASSIGNEE TO UNDERWOOD TYPE-
WRITER COMPANY, OF NEW YORK, N. Y., A CORPORATION OF DELAWARE.

TYPEWRITING MACHINE.

Application filed October 16, 1919. Serial No. 330,971.

To all whom it may concern:

Be it known that I, CORNELIUS B. CORCORAN, a citizen of the United States, residing in borough of the Bronx, in the county of the Bronx, city and State of New York, have invented certain new and useful Improvements in Typewriting Machines, of which the following is a specification.

This invention relates to typewriting machines, and more especially to the signaling mechanism which is used for indicating the approach to the end of a line of writing. The invention is herein disclosed as applied to an Underwood standard typewriting machine, one form of which is disclosed in the patent to Pfunder and Cook, No. 853,562, of May 14, 1907, and another form of which is disclosed in the co-pending application of Helmond, No. 279,081, filed February 25, 1919.

Such line-end signaling mechanism usually includes a bell for notifying the typist that the end of the line has almost been reached, and where typewriting machines are used in noisy places, or where a typist is trying to write very fast, extraordinarily large bells have frequently been used to enable the typist to be forcibly reminded that the end of the line is approaching. It has been found that such very large bells are unnecessary if instead thereof two bells of smaller or a usual size are employed, especially if such bells are of different and discordant tones. Such two bells may be rung by a single clapper mechanism, which may be for the most part identical with that hitherto in use, or that disclosed in said application No. 279,081.

By thus using two bells, preferably of discordant tones, the loud noise incident to the use of a louder bell, with its distracting effect on other typists, is avoided, while at the same time the efficiency of the signal is in no way diminished and may be actually increased.

Other features and advantages will hereinafter appear.

In the accompanying drawings,

Figure 1 is a fragmentary skeleton perspective view of an Underwood typewriting machine embodying many of the features shown in said application No. 279,081.

Figure 2 is a sectional plan view of the two bells and the clapper.

In the Underwood typewriting machine, 55 the carriage 1 comprises a platen 2, which is revolvable therein and travels with the carriage, so that types 3 of the usual form print against the front of it at the letter-space noted by the usual pointer mounted upon 60 the usual carriage lug 4. When the typewriter carriage approaches the end of the line which the typist has determined is of the proper length, the usual tappet 5 rides upon the usual cam 6, which latter is shift- 65 able with the usual left-hand margin stop, with the result that the tappet 5 swings the cam 6 and causes the cam to swing forwardly a depending arm 8, which may be of the form shown in said patent or applica- 70

The swinging forward of the arm 8 causes a one-way tappet 9, pivotally attached to the lower end thereof, to sweep forwardly over a cam 10 of a bell-ringing arm 11, with the 75 result that the tappet 9 depresses the front end of the arm 11, swinging it around its pivot 12, and then releases the arm, so that the hammer 13 at the rear end thereof is first raised and at the releasing of the arm drops 80 upon a bell 14. This rings the bell and notifies the typist that the carriage 1 has almost reached the limit of its travel.

In order to enable the hammer 13 to operate efficiently, the rear end of the arm 11 is 85 formed as a resilient wire 15, which supports the hammer 13 within the periphery of the bell 14 and enables the bell to be easily adjusted by bending the wire 15. According to the present invention, the bell 14, which is 90 held by a bolt 16 upon the usual lug 17, extending upwardly from the bottom bar 18 of the frame, has adjacent thereto a second bell 19 carried by an upper extension 20 of the bolt 16. The bell 14 may be held 95 against the lug 17 by a shoulder 21 on the bolt 16, and the bell 19 may be spaced from the bell 14 by a suitably positioned second shoulder 22 on the extension 20 of the bolt, and be held in position by a nut 23 screwed down outside the bell 19 to force it against the shoulder 22. The tightening of the nut 23 screws the bolt 16 down into a threaded opening 24 in the lug 17, thus tightening both bells in place with their bases near each 100 other but separated enough to let the wire 15 swing clear. For ringing the bell 19, there is preferably provided a second ham-

mer 25, so arranged that the hammers 13 and 25 strike the bells substantially simultaneously.

- The hammers may be formed as a single clapper elongated transversely of the wire 15 and having two heads, onto the junction of which the wire 15 is twisted to enable it to hold the hammers. The hammers 13 and 25 of the duplex clapper, as clearly appears from Figures 1 and 2, do not engage the edges of the bells 14 and 19, but extend within the bells far enough to engage them squarely at some distance from their edges. It has been found that two bells having tones three steps apart from a considerable improvement over a single bell, but that if the two bells, instead of being thus tuned to harmony, are tuned to discordant tones, they are more effective.
- It is difficult to arrange a clapper so as to cause it to engage two or more bells at exactly the same time, and it is even more difficult to preserve an arrangement of parts in which a clapper will engage a plurality of bells at exactly the same time. In the use of a single clapper with a plurality of bells, the parts, due to the impact of the clapper on the bells, will soon be thrown out of alignment so that the clapper will engage one of the bells before the other, and if the clapper is of usual construction it may ring only the bell with which it first engages. In the use of a duplex clapper, such as is hereinbefore described, however, the engagement of the clapper with each of the bells is assured, since, if one of the hammers of the duplex clapper engages its bell before the other, the clapper will tilt in a plane transverse to the plane of movement of the clapper as a whole, so as to cause the other hammer of the clapper to engage its respective bell only very slightly after the engagement of the first hammer with its bell. This action of the clapper is facilitated by the fact that the wire 15 is arranged in a plane intermediate between the planes of movement of the hammers 13 and 25, and by the further fact that the wire is resilient so that the clapper may readily tilt to the degree required to bring both of the hammers into engagement with their respective bells.

It will be noted that the two bells thus mounted interfere with no other mechanism in the usual Underwood standard typewriting machine, and that they in nowise interfere with the operation of the usual type-key-locking bar 26 by the arm 8.

It will also be noted that the degree of loudness of the bells may be below the normal which would ordinarily be required for given working conditions. Thus, in ordinary working conditions, the degree of loudness of the signal might be below that of

the bell of usual size, the bells of the pair being of less than the usual size. In this way an effective signal would be given with a minimum of noise.

Variations may be resorted to within the scope of the invention, and portions of the improvements may be used without others.

Having thus described my invention I claim:

1. In a typewriting machine, the combination with a traveling carriage and a platen, of a machine frame, a bell, a bolt mounted on said frame to hold the bell, a second bell of different tone supported by the bolt, said bells having their bases adjacent to each other, a single clapper for the two bells, means made effective by the carriage travel for operating the clapper to ring said bells, and connections between the clapper and its operating means constructed to enable the clapper to tilt in a plane transverse to the movement of the clapper as a whole to assure that both of the bells will be rung upon operation of the clapper, said clapper being elongated transversely of the direction of its movement so as to engage the bells at points spaced by substantial distances from the edges of the bells and from the plane of movement of the connections at their juncture with the clapper.

2. In a typewriting machine, the combination with a traveling carriage and a platen, of a machine frame, two bells upon the frame, a single duplex clapper comprising hammers arranged for striking engagement with the respective bells, means made effective by the carriage travel for operating the clapper to ring the bells, and a connection between the clapper and its operating means, said connection being resilient to enable the clapper to tilt readily to the degree required to bring both of the hammers into engagement with their respective bells.

3. In a typewriting machine, the combination with a traveling carriage and a platen, of a machine frame, two bells upon the frame, a single duplex clapper comprising hammers arranged for striking engagement with the respective bells, means made effective by the carriage travel for operating the clapper to ring the bells, and a connection between the clapper and its operating means arranged in a plane intermediate between the planes of movement of the hammers toward and away from the bells and being resilient to enable the clapper to tilt readily to the degree required to bring both of the hammers into engagement with their respective bells.

CORNELIUS B. CORCORAN.
